H. W. BUTTERWORTH.
STEAM DRYING CYLINDER.

No. 66,075.

Patented June 25, 1867.

United States Patent Office.

H. W. BUTTERWORTH, OF PHILADELPHIA, PENNSYLVANIA.

Letters Patent No. 66,075, dated June 25, 1867.

IMPROVEMENT IN STEAM-DRYING CYLINDERS.

The Schedule referred to in these Letters Patent and making part of the same.

TO ALL WHOM IT MAY CONCERN:

Be it known that I, H. W. BUTTERWORTH, of Philadelphia, Pennsylvania, have invented an improved Bearing for Drying-Cylinders; and I do hereby declare the following to be a full, clear, and exact description of the same.

My invention consists of a stand containing a chamber, in combination with the tubular spindle of a drying-roller, and with a packing-ring and follower, the whole being constructed and arranged, as fully described hereafter, so that the escape of steam in its passage from and to the cylinder is prevented, and so that the follower may be adjusted without interfering with the operation of the machine.

In order to enable others skilled in the art to make and use my invention, I will now proceed to describe its construction and operation, reference being had to the accompanying drawing, which forms a part of this specification, and in which—

Figure 1 is a vertical section of my improved bearing for drying-cylinders.

Figure 2, an end view of the same; and

Figure 3, a vertical section of a modification of my invention.

A is a tubular spindle, a disk, *a*, on which, is secured to one end of a drying-cylinder, *b*, shown by red lines. A portion of the spindle is reduced in diameter, and fits snugly, but so as to turn freely in the projection *d* of the bearing or stand *B*, and in the vertical portion *e* of the latter is a passage, *f*, communicating with a chamber, *h*, into which the end of the tubular spindle *A* projects. Between this projecting portion of the spindle and the interior of the chamber *h* is an annular recess for receiving a packing-ring, *i*, and an annular portion, *j*, of a follower, *D*, radial arms projecting from this annular portion to a central hub, *m*, of the follower, and into this hub screws the end *n* of the stud or set-screw *E*, a collar, *p*, on which bears against the inside of a cap, *F*, bolted to the stand or bearing *B*, and enclosing the chamber *D*. A portion, *q*, of the stud *E* passes through and is arranged to turn in the cap *F*, the stud having a square or other suitably formed end for receiving a screw-key or other like instrument, by which the stud can be turned and the follower forced against the packing-ring, so that the latter may form a perfectly tight joint round the tubular spindle. In fig. 3 the stud *E* is of a different character, passing freely through, and not turning in the hub *m* of the follower, against which, however, bears a nut, *t*, adapted to the screw-thread on the stud, the end of the latter fitting into a recess in the inside of the cap *F*, not passing through the same, as in fig. 1.

The nut *t* is first adjusted to what may be considered the proper position on the stud, after which the cap is applied to its place, the act of tightening the cap forcing the follower against the packing. In either case so tight a joint is made round the tubular spindle that the steam, in its passage through the stand and spindle into the cylinder on one end of the same, and from the cylinder through the stand at the opposite end, cannot escape and damage the warp or other object on which the cylinders have to be brought to bear. By removing the cap *F* ready access may be had to the packing-ring *i*, while the follower may be adjusted by turning the stud *E*, without the necessity of opening the chamber *h* or interfering with the operation of the machine.

I claim as my invention, and desire to secure by Letters Patent—

1. The standard or bearing *B*, with its chamber *h* and opening *f*, in combination with the tubular spindle *A*, projecting into the said chamber, a packing-ring, *i*, and follower *D*, or its equivalent, the whole being constructed and arranged substantially as and for the purpose described.
2. The combination of the follower *D* and a screw-stud turning in the follower and projecting through the stand, substantially as and for the purpose set forth.

In testimony whereof I have signed my name to this specification in the presence of two subscribing witnesses.

H. W. BUTTERWORTH.

Witnesses:

CHARLES E. FOSTER,

JOHN WHITE.
